WORK HOLD-DOWN DEVICE

Charles Rubenstein, Kansas City, Mo.

Application December 26, 1944, Serial No. 569,752

3 Claims. (Cl. 90—61)

1

This invention relates to attachments for work-holding machines in the character of shapers or the like, and has for its primary aim to provide means for directly engaging the material constituting the work, and for securing said work not only between the retaining clamps of the machine, but tightly against the underlying support.

One of the primary aims of this invention is to provide a work hold-down for shapers or the like, adapted for re-positioning between the material and the clamps and having at least one specially formed part, disposed to convert a portion of the pressure exerted by the clamps into force holding the work against the bed of the machine.

This invention has for an even further aim to provide a work hold-down of the aforementioned character, which includes a specially disposed blade, positioned at an angle with respect to the direction of travel of the retaining clamps, which blade is resilient, divided into sections, and specially designed to insure a positive grip and an engagement that will not accidentally loosen and which will preclude upward movement of the work from its normal place upon the surface of the machine bed.

Other objects of the invention will appear during the course of the following specification, referring to the accompanying drawing, wherein:

Fig. 1 is a front elevational view in perspective of a work hold-down made in accordance with the present invention and showing the same in operative position on a shaper.

Fig. 2 is a top plan view of the work hold-down per se.

Fig. 3 is an end elevational view thereof.

Fig. 4 is a cross sectional view through the hold-down, taken on line IV—IV of Fig. 2; and

Fig. 5 is a similar cross sectional view illustrating a hold-down made pursuant to a modified form of the invention.

Heretofore horizontally movable clamps for holding the material constituting work receiving attention, have failed to maintain the work in a position tight against the upper surface of the bed of the shaper. It is difficult to supplement the clamps or position the same to exert a downward pressure, and since such pressure is essential, the hold-down blocks embodying this invention are practically indispensable before the work can be perfectly set.

In the drawing wherein like reference characters refer to similar parts, the numeral 10 designates a shaper of conventional type having as a part thereof, a pair of opposed clamps 12 and

2

14 above a bed 16, and movable in horizontal paths thereabove. In short, the direction of travel of clamps 12 and 14 is parallel to the top of bed 16, whereupon work 18 is positioned.

The work, in this instance, is illustrated as a polygonal solid having opposed vertical surfaces 20, against which the hereinafter described hold-down members are forced.

The hold-down per se comprises a body 22 shaped, in its preferred embodiment as illustrated in Figs. 2, 3 and 4, and formed of material capable of withstanding the pressure and having resilient characteristics to the end that the downwardly and forwardly inclined blade 24 constituting a part thereof, may flex.

In the form illustrated, blade 24 is created by longitudinally milling body 22 to establish a groove 26. A tongue 28 is disposed below groove 26 to present a base for body 22. The edge of

body 22 engaged by the adjacent clamps 12 or 14 as the case may be, is longitudinally milled to form a depression 30 on either side of which is a flat face 32. These flat faces 32 are in the same vertical plane and face 34 of tongue 28 is at right angles to the plane wherein faces 32 are disposed.

The forward lowermost free edge of blade 24 is relatively thin and this edge 36 projects outwardly beyond the underlying edge 40 of tongue 38.

When the hold-down is in place, as illustrated in Fig. 1, faces 32 lie against the smooth inner surface of the adjacent clamp and surface 34 lies upon the normally horizontal face of bed 16. Inward movement of the clamp which exerts the force toward work 18, will drive edge 36 against work 18 and not only force said work downwardly against bed 16, but grip the same as would be the case if only clamps 12 and 14 were used.

A number of transverse slits 42 formed in blade 24 divide said blade 24 into a plurality of sections 44. Thus, any irregularity of the face of work 18 against which the hold-down is being moved, will not effect the position or function of body 22. On the contrary, the several sections 44 will flex to different degrees to compensate for such irregularities and a positive inward and downward pressure will be applied to work 18.

In the modified form of the invention illustrated in Fig. 5, body 100 carries the flexible blade 102 assembled with body 100 after being separately manufactured. This blade is downwardly and forwardly inclined however, in the same manner as is blade 24, and its lowermost free edge 104 projects beyond edge 106 of the body. A series of pins 108 projecting upwardly through

openings 110 cooperate with groove 112 in maintaining blade 102 in the operative position illustrated in Fig. 5.

Body 100 is formed to present a fulcrum 114 about which plate 102 may rock. This rocking is limited by the width of groove 112 and when pressure is exerted against smooth surfaces 116, blade 102 will arch and increase the amount of force that is applied to the work in a direction toward the supporting underlying bed 16.

Obviously, the basic function of both forms of the hold-down illustrated and described, is the same. The conversion of the pressure exerted by clamps 12 and 14 into force holding the work against the bed of the machine, as well as holding the work between the clamps, is the result of using the hold-down blocks, and therefore, there is no danger of mal-adjustment due to undesirable upward displacement of the work.

The manner of constructing hold-downs made in accordance with this invention, and their specific appearance may be different from that above described and illustrated in the accompanying drawing. It is desired, therefore, to be limited only by the spirit of the invention and scope of the appended claims.

Having thus described the invention, what is claimed as new and desired to be secured by Letters Patent is:

1. A hold down of the character described for use in material shaping machines having a work supporting bed and a clamp for exerting pressure against the work in a direction substantially par-

allel to the top of the bed, said hold down comprising a body adapted for positioning between the work and said clamp, said body having a flexible, downwardly inclined, transversely archable portion formed to convert a portion of the pressure exerted in said direction into force holding the work against the bed of the machine, said resilient portion being divided into a plurality of independent sections all engaging the work and all receiving pressure from the clamp.

2. A hold down of the character described for use in material shaping machines having a work supporting bed and a clamp for exerting pressure against the work in a direction substantially parallel to the top of the bed, said hold down comprising a body adapted for positioning between the work and said clamp, said body having a downwardly inclined flexible blade formed to arch as the pressure exerted in the aforesaid direction by the clamp is applied whereby a portion of said pressure is converted into force holding the work against the bed of the machine, said blade being transversely divided into a plurality of independently archable sections.

3. A work hold down of the character described, comprising a unitary body; a resilient blade on the body extending longitudinally along one side thereof and disposed at an angle to the face of one side of the body and beyond the edge of the body at the lowermost portion of the blade, said blade being divided into a number of sections comprising its length.

CHARLES RUBENSTEIN.
